United States Patent Office.

BENJAMIN D. WASHBURN, OF BOSTON, MASSACHUSETTS.

Letters Patent No. 94,363, dated August 31, 1869.

IMPROVED SHUTTER-FASTENING.

The Schedule referred to in these Letters Patent and making part of the same.

To all whom it may concern:

Be it known that I, BENJAMIN D. WASHBURN, of the city of Boston, county of Suffolk, and State of Massachusetts, have invented a new and useful Improvement in Window-Blind Fastenings; and I do hereby declare that the following is a full, clear, and exact description of the construction and operation of the same, reference being had to the drawings accompanying this specification, and making a part thereof, panying this specification, and making a part thereof.

Figure 1 is a perspective view of my fastening.

Figure 2, the spring that operates the hook, or catch; and

Figure 3, a sectional longitudinal view, showing the locality of the different parts.

The nature of my invention consists in the construction of a window blind fastening, in such a manner as that it can easily be applied to any window blind of very simple and cheap construction, and not liable to get out of order.

To enable others skilled in the art to make and use my invention, I will proceed to describe its construction and operation.

The shell or case of this fastening is made preferably in one piece, as shown at B. On its external surface screw-threads are cut so that upon boring a hole in the blind, a little less than the diameter of the shell or case, it can be screwed into the same with little or no difficulty.

At each end of the shell or case are tips or prolongations, x x, on the inner side of which are cut or cast slots, d d.

The hook A is placed within the shell or case, and pivotted centrally therein at e.

The spring C is attached in the manner shown in the drawing, and keeps the hook A closed or in contact with the case or shell B.

The points of either end of the hook A as, repre-

sented at f f, are retained in the slots d d, contained in the tips or projections x x; by this form of construction there can be no lateral displacement of the hook, and when the case or shell is screwed into the blind, a sufficient purchase is given to it, and seldom requiring anything but the hand to put it in position.

Were it not for the slot above referred to, in screwing the case or shell into the blind, there would be a great liability to bend or break the hook A. By this construction such a result is rendered impossible.

A staple or other suitable device is driven into the wall of the building at such a point thereon that when the blind is thrown back, it will force open the hook A, and is at once clasped by the same and held firmly in position. To release the blind, it is only required to raise the hook A at the opposite side, and close the same. Upon the window-sill a like staple, or suitable device, is attached, to which the blind is fastened and closed.

My invention can also be applied to a case or shell made in two parts, so that the tip or projection can form a part of the same, and contain the slots herein referred to, and for the purposes described.

What I claim as my invention, and desire to secure by Letters Patent, is—

1. In window-blind fastenings, the projections x x, upon either or both ends of the shell, or case, when such tips or projections contain the slots d d, in the manner and for the purpose herein described.

2. The combination of the hook A, shell B, tips x x, and slots d d, in the manner and for the purpose herein described.

B. D. WASHBURN.
